(57) **CLAIM**

The ornamental design for a mounting bracket and support arm for an exterior vehicle mirror assembly, as shown and described.

DESCRIPTION

FIG. 1 is a rear perspective view of the mounting bracket and support arm design;

FIG. 2 is a front perspective view of the mounting bracket and support arm design;

FIG. 3 is a front elevation view of the mounting bracket and support arm design;

FIG. 4 is a rear elevation view of the mounting bracket and support arm design;

FIG. 5 is a right side elevation view of the mounting bracket and support arm design;

FIG. 6 is a left side elevation view of the mounting bracket and support arm design;

FIG. 7 is a top plan view of the mounting bracket and support arm design; and,

FIG. 8 is a bottom plan view of the mounting bracket and support arm design.

In the drawings, the broken lines depict a portion of a support arm and the interior boundary of a mounting bracket and support arm for exterior vehicle mirror assembly and form no part of the claimed design.
